DEMONSTRATING DEVICE FOR SUCTION
CLEANERSHarry B. White, Canton, Ohio, assignor to The
Hoover Company, North Canton, Ohio, a cor-
poration of Ohio

Application June 10, 1949, Serial No. 88,235

6 Claims. (Cl. 35—13)

1

The present invention relates to suction cleaning devices and in particular to a filter structure designed to be inserted in a suction air conduit adapted to be connected to suitable dusting tools. Another object of the invention is to provide a small filter mounting device which forms a rigid, continuous portion of the dusting tool air conduit and includes structure permitting facile insertion and removal of small filtering strips without hinging sections of the hose with respect to each other and without disconnecting the filtering device from the dusting tool wand.

It is a further object of the present invention to provide an improved dirt trap construction which is adapted to form a part of a dusting tool unit.

Other objects and advantages of the invention will become apparent in connection with the following specification and claims and upon considering the attached drawing in which:

Figure 1 is a side view partly in section illustrating my improved filtering unit mounted in a dusting tool suction air conduit; and

Figure 2 is a perspective view drawn upon a smaller scale illustrating the filter unit per se with the filter cover in open position.

The unit or accessory comprising the present invention is adapted to be removably connected to a dusting tool unit to form a part of the air conduit between a dusting tool and a suction cleaner proper. Its function is to filter the dirt carrying air which passes through the dusting tool unit in response to the suction created by the cleaner, and to remove from that air, for a relatively short period of time, the foreign matter therein contained for purposes of illustration to a prospective purchaser of the cleaning properties of the dusting tool.

Referring to the drawing in detail and first to Figure 2 the unit comprises a central housing 1, which may be a casting, adapted to house a small sheet of filtering material 2 such as paper as will appear more fully hereinafter. One end of the housing 1 carries a short extending conduit section 3 adapted to be connected, for example, to the usual dusting tool hose of suction cleaning element. The other end of the housing 1 carries a short conduit section 4 having, in the illustrated embodiment, a reduced end section 5 which is adapted to be connected to a manipulating wand or the like which carries a dusting tool on its end.

As shown more particularly in Figure 1, the conduit section 4 is shown broken and connected directly to a bristle carrying suction air cleaning

2

dusting tool 6 which may be used for various cleaning purposes.

The conduits 3 and 4 telescope into hollow sockets 8 and 9 respectively in the housing 1 and are secured therein as by rivets 10 and 11 respectively.

The central portion of the housing 1 between the sockets 8 and 9 is enlarged and comprises substantially flat bottom wall 7 joining flat up-
10 standing side walls 14 which merge into a rounded top wall 19. The top wall 19 and side walls 14 are removed along the lines formed by a pair of planes intersecting at an angle of approximately 90° and cutting a vertical transverse
15 plane through the center of housing 1 at an angle of approximately 45° to form a deep V-shaped notch 12. A barrier wall 13 rises from the bottom wall 7 to the line of the apex of the notch 12. As shown in Figure 1 the wall 13 rises gradually from the wall 7 on each side of its apex to reduce turbulence in the suction air stream which flows through housing 1 in use.

A perforated rigid screen 15 is mounted within the housing 1 having its lower edge engaging in
25 a notch 16 at the upper edge of the partition 13 and its top and side portions resting against a seat 17 extending along the side and top edges of the right hand or upstream, Figure 1, side of the notch 12. A bolt 18 extends through the screen 15 and into the body 1 to anchor the screen firmly in place.

The down stream portion of the housing 1 ad-
30 jacent to the conduit 4 is provided with a pair of spaced upstanding ears 20 at the upper portion thereof and slightly rearwardly of the down stream face of the notch 12. The ears 20 support a pintle 21. The pintle 21 pivotally supports a cover 22 for the notched out portion 12 of the housing 1. The cover 22 is provided with a straight top portion 23 which supports V-
35 shaped side wings 24 adapted to fit into the notch 12 and completely close the same.

The squared off top portion of the cover 23 ex-
40 tends rearwardly of the limits of the notch 12 and includes a downwardly facing seat 26 engaging around the pintle 21. The bottom portion of this seat is closed by a hardened plate 27 secured to the square top portion 23 of cover 22 by a rivet 28. The pintle 21 is so placed with reference to the
45 notch 12 that the cover closes the notch 12 with the edges of the side wings 24 engaging the edges of the notch to complete an air conduit through the housing 1. The sheet of filter material 2 rests on and covers the perforated plate 15. The filter 2 is secured in place by being clamped be-
50
55

tween the edges of the cover 22 and the notch 12.

The filter housing 1 is provided with an up-standing spring housing 30 adjacent and rearwardly of the pintle 21 and the supporting ears 20 therefor. A stiff leaf spring 31 is mounted in the housing 30 and is secured thereto by means of a rivet 32. As clearly shown in Figure 1 the projecting portion of the leaf spring 31 underlies the rear edge of the hardened plate 21 so that in the position shown the force of the spring urges the closure 22 into the closed position shown in Figure 1 to form a tight seal with the edges of the notch 12 and against the filter paper 2. When the cover 22 is moved to open position it pivots through an arc which is greater than 90° to a stop position in which the top portion 23 of the cover abuts an end of the housing 30. Since the rear edge of the plate 21 crosses to the right hand upstream side of a line from the center of the pintle 21 perpendicular to the face of the spring 31 when the cover is opened, the spring 31 urges the cover to open position. That is, the spring 31 resiliently retains the cover 22 in both open and closed positions and is in effect a snap acting device for this purpose.

In the use of the device, the filter housing comprising the casing 1 and its associated parts including the conduit section 3 and 4 are connected in a dusting tool hose and wand assembly between the suction cleaner and a dusting tool such as the element 6. These parts are assembled with the conduit section 3 connected to that part of the hose and wand system which is closest to the suction cleaner and hence upstream with reference to the direction of air flow. The cover 22 is then snapped to the open position shown in Figure 2 and a small sheet of filtering material 2, such as paper, is placed within the notched out portion of the housing 1 against the plate 15. The cover 22 is now snapped to closed position which seals the interior of the housing and firmly secures the filter sheet 2 in place against the screen 15. The suction cleaning apparatus is now operated in the usual manner to clean furniture, walls, draperies, rugs or other material during the course of which the dirt picked up will flow through the tool 6 and conduit 4 into the housing 1 and be caught upon the filter material 2. After a short period of cleaning operation the suction cleaner is shut off and the cover 22 is moved to open position to allow removal of the paper 2 so that a prospective purchaser may have visual evidence of the dirt which was removed by the dusting tool 6.

If desired the upper squared out portion 23 of the cover 22 may include a transparent insert so that the accumulation of dirt upon the filter 2 may be watched as the cleaning operation progresses.

The present invention provides a simple, effective filtering element for suction cleaning dusting tool suction air conduit which always forms a continuous rigid portion of the air conduit and allows ready insertion and removal of filtering material without breaking, or pivoting the rigid connecting conduit which carries the filtering element.

While I have illustrated and described the invention in considerable detail, it is to be understood that various changes may be made in the arrangement, proportion and construction of parts without departing from the spirit of the invention or the scope of the appended claims.

I claim:

1. A dusting tool filter element comprising a hollow body adapted to be connected into and to

form a part of a suction air conduit, said body having an opening extending across its top wall and part way through opposite side walls thereof, a closure plate for said opening including wall portions adapted to contact the edges of said opening in said body to seal the air passageway through said body, a partition structure extending entirely across the interior of said body including an imperforate section extending from the bottom wall thereof to the edges of said opening and a perforated section extending from the end of said imperforate section to the side and top wall edges of one side of said opening.

2. A filter element comprising a hollow body adapted to be connected into and form a part of a suction air conduit, said hollow body including a filter section having a deep V-shaped notch cut therein with the apex of the said notch terminating above the bottom wall of said hollow body, a partition extending across the interior of said hollow body including an imperforate section extending from said bottom wall up to the apex of said V-shaped notch and a perforated section extending in the plane of one side of said V-shaped notch from the top of said imperforate partition to said top wall, and a cover member shaped to fit said V-shape notch mounted on said body for movement into open and closed positions.

3. A filter element comprising a hollow body adapted to be connected into and form a part of a suction air conduit, said hollow body including a filter section having a deep V-shaped notch cut therein with the apex of the said notch terminating above the bottom wall of said hollow body, a partition extending across the interior of said hollow body including an imperforate section extending from said bottom wall up to the apex of said V-shaped notch and a perforated section extending in the plane of one side of said V-shaped notch from the top of said imperforate partition to said top wall, and a closure member for said V-shaped notch including a top portion and V-shaped side portions adapted to engage the marginal edges of said notch to seal the same, said closure member being mounted on said body for movement into open and closed positions with respect to said notch.

4. A filter element comprising a hollow body adapted to be connected into and form a part of a suction air conduit, said hollow body including a filter section having a deep V-shaped notch cut therein with the apex of the said notch terminating above the bottom wall of said hollow body, a partition extending across the interior of said hollow body including an imperforate section extending from said bottom wall up to the apex of said V-shaped notch and a perforated section extending in the plane of one side of said V-shaped notch from the top of said imperforate partition to said top wall, and a closure member for said V-shaped notch including a top portion and V-shaped side portions adapted to engage the marginal edges of said notch to seal the same, said closure member including a portion projecting beyond the face of said notch opposite to said screen, means on said body pivotally mounting said projecting portion of said cover member, and a flat leaf spring secured to said body and having a projecting portion bearing on the underside of the projecting portion of said cover member on the side of said pivotal mounting means remote from the notch closing portion of said cover member.

5. A dusting tool suction air conduit filter ele-

ment comprising a tubular body adapted to form part of a suction air conduit, said body having a portion thereof cut away to form a wide mouth opening in the top thereof, a partition extending from the bottom wall of said body to a junction with the margins of said opening, a screen extending across the body from the upper edge of said portion along one margin of said opening and a cover plate movably mounted on said body, said cover plate being shaped to engage the margins of said opening to close the same.

6. A dusting tool suction air conduit filter element comprising a tubular body adapted to form part of a suction air conduit, said body having a portion thereof cut away to form a wide mouth opening in the top thereof, a partition extending from the bottom wall of said body to a junction with the margins of said opening, a screen extending across the body from the upper edge of said portion along one margin of said opening, 20

a cover plate shaped to engage the margins of said opening to close the same, means pivotally mounting said cover plate on said body, and snap acting means on said body engaging said cover plate for resiliently maintaining said cover plate in fully open or fully closed positions.
